UNITED STATES PATENT OFFICE.

GEORGE B. KEPLINGER, OF CHICAGO, ILLINOIS.

BATH-BRUSH.

1,367,747.

Specification of Letters Patent. Patented Feb. 8, 1921.

Application filed May 7, 1919. Serial No. 295,475.

To all whom it may concern:

Be it known that I, GEORGE B. KEPLINGER, citizen of the United States, residing at Chicago, in the county of Cook and State of Illinois, have invented certain new and useful Improvements in Bath-Brushes; and I do hereby declare the following to be a full, clear, and exact description of the invention, such as will enable others skilled in the art 10 to which it appertains to make and use the same.

This invention has for its object to provide what might be termed a bath brush adapted for use on the person to effect thorough cleansing of the skin and has for its 15 object to provide a simple and efficient device of this character which may be readily and efficiently used upon any part of the person.

20 The invention consists in features of construction and combinations of parts hereinafter fully described and particularly claimed.

In the accompanying drawings illustrating 25 a suitable embodiment of the invention:

Figure 1 is a view in elevation of a cleansing device constructed in accordance with the invention.

Fig. 2 is a transverse section of the same 30 on the line 2-2 of Fig. 1.

Fig. 3 is a detail section of one of the pneumatic friction elements on the line 3-3 of Fig. 1.

Fig. 4 is a view similar to Fig. 1 showing 35 a modified form of construction of the device.

My said device comprises a strip 1 of fabric of any suitable nature such as cotton duck or the like having tapered end portions 40 2 to which loops 3 are secured, the latter being adapted to be passed over the thumbs or fingers of the hand of the operator for manipulating the device.

Mounted upon one face of the strip 1 at 45 regular intervals and preferably at an incline to the parallel side edges thereof, is a plurality of short sections 4 of rubber tubing which are sealed at their ends by collapsing the walls of the tube sections upon 50 each other and cementing or vulcanizing them together at their ends as shown in Fig. 3 so as to trap the air contained in the bodies of the tubes. The collapsed end portions provide flat ends 5 for the tubes

which are thus adapted to be and are secured upon one face of the strip 1 by means of lines of stitching 6, for example, though obviously said tubes may be secured in any other suitable or desirable manner adapted to the purpose.

It will be noted by reference to Fig. 1 that the tubes may be arranged in two series at opposite end portions of the strip so that the tubes of one set are inclined in the opposite direction from the other set. The 60 inclination of the tubes is desirable so that in moving the strip longitudinally over various portions of the person, the effect will be similar to a continuous rather than an intermittent friction. The tubes being very 65 flexible and being filled with air, as aforesaid, renders them very soft and cushion-like so that when applied to the skin, they will yield to pressure and a considerable part of the surface of each thereof will be flattened against the skin as the strip 1 is tautly drawn around any portion of the body, thus producing a relatively mild but 70 efficient frictional contact between the surface of each tube and the skin over which 75 it is passed thereby effecting a thorough cleansing without, however, occasioning any discomfort to the user.

The several tubes 4 may also be arranged upon one face of the strip as shown in Fig. 85 4 where they present a substantially zig-zag formation, but it will be obvious that the relative positioning of the tubes may be changed and varied at will without departing 90 from the invention.

While I have shown the preferred embodiment of the invention in the accompanying drawings, it will be understood, of course, that the constructions shown and described may be changed and varied as mechanical skill may suggest to best adapt the same to perform the intended functions without departing from the invention as defined in the appended claims.

I claim as my invention:

1. A cleansing device comprising a strip of fabric provided on one of its faces with laterally extending sections of rubber tubing having collapsed, hermetically sealed ends and fastening means passing through 105 the collapsed ends of said tubes and through the edge portions of said strip of fabric.

2. A cleansing device comprising a strip

of fabric provided on one of its faces with two series of short rubber tubes having flat, collapsed, hermetically sealed ends, the tubes of each series being parallel with each other 5 and extending angularly substantially transversely of said strip, and the two series thereof being disposed at opposite inclina-

tions and at opposite end portions of said strip, and lines of stitching passing through the edge portions of said strip of fabric and 10 through the flat collapsed ends of said tube sections for securing the latter to said strip.

GEORGE B. KEPLINGER.
